UNITED STATES PATENT OFFICE

NOAH B. KENDRICK, OF MOUNT HOLLY, NORTH CAROLINA

MEANS FOR BURNING BRICK

Application filed April 12, 1932. Serial No. 604,758.

This invention relates to brick making and more especially to a process of burning brick by connecting the draft forming means for the kilns thru a plurality of kilns in series so that it is possible in the burning of one kiln to cause the draft created in the first kiln to be drawn thru a second kiln and into the draft forming duct so that the heat will not be entirely wasted but will be used for pre-heating the next kiln. When the first kiln has been burned properly the duct leading from the first kiln to the second kiln can be closed and the duct leading from the second kiln to the third kiln can be opened and in that way the heat drawn from the kiln in which the fire is being maintained will be used for pre-heating the next succeeding kiln, consequently, a great saving of expense and time in burning brick in the kilns is effected.

It is, of course, evident that this invention is not to be limited to the burning of brick in the kilns as it is evident that the kilns may be filled with tiles, earthen pipes, insulators, and in fact any objects made of ceramic materials.

Some of the objects of the invention having been stated, the method and means will more fully hereinafter appear when taken in connection with the accompanying drawings, in which—

Figure 1 is a plan diagrammatic view of a brick yard showing a plurality of kilns connected in series and provided with a circular draft duct for creating a draft in the kilns and also being provided with a circular draft duct for withdrawing the heat from the kilns after the fire has ceased burning therein;

Figure 2 is a cross sectional view taken along line 2—2 and showing one kiln in section and the next succeeding kiln in elevation;

Figure 3 is a plan view of another arrangement of the kilns but embodying a slightly different arrangement of the ducts for exhausting the kilns and creating a draft therein;

Referring more specifically to the drawings, the diagram in Figure 1 shows the kilns and ducts therefor arranged in cir-

cular formation so that a continuous process can be carried out. The reference character 10 indicates an underground circular duct for creating a draft thru the kilns having a passageway 11 leading to an exhaust fan 12 driven by any suitable means such as a motor 13 and exhausting as at 14.

Reference character 15 indicates a circular duct for removing the heat from the kilns after the burning operation has been completed and this has a passageway 16 having an exhaust fan 17 driven by any suitable means such as a motor 18 and exhausting as at 19. A plurality of kilns 20, 21, 22, 23, 24 and 25 are provided. A duct 26 leads from cooling duct 15 to the bottom central portion of kiln 20 and has a gate 27 therein. A duct 28 communicates with the lower central portion of kiln 20 and runs underground to draft duct 10 and has a gate 29 therein. An underground duct 30 extends from duct 28 to a vertical stack 31 extending above the top of kiln 21 and a suitable duct or pipe 32 leads into the top of kiln 21. Duct 30 has a gate 33 therein.

Kiln 21 has a duct 34 connected to cooling duct 15 which has a gate 35 therein. This duct 34 connects to the lower central portion of kiln 21 as is evident in Figure 2. A duct 36 is connected to the lower central portion of kiln 21 and leads to draft duct 10 and a gate 37 is disposed in said duct 36.

Leading from duct 36 is an underground duct 38 having a gate 39 therein and this duct 38 connects to the lower embedded portion of vertical stack 39 extending above the top level of kiln 22 and a pipe or any suitable duct 40 leads into the top of kiln 22.

Kiln 22 has an underground duct 41 communicating with cooling duct 15. Duct 41 has a vertically slidible gate 42 therein. Duct 41, likewise, extends beneath kiln 22 and communicates with the central lower surface thereof. A duct 43 having a gate 44 therein communicates with the opening in the floor of central portion of kiln 22 and is connected to draft duct 10. An underground duct 45 having a gate 46 therein leads from duct 44 to vertically disposed stack 48 and from the top of stack 48 a pipe or other

suitable duct 49 leads into the top of kiln 23.

Kiln 23 has communicating with the central portion of the floor thereof a duct 50 having gate 51 therein, said duct 50 communicating with cooling duct 15. A duct 52 communicates with the central floor portion of kiln 23 and also draft duct 10 and has a gate 53 therein.

Duct 52 has communicating therewith duct 54 which has gate 55 therein, said duct 54 communicating with vertically disposed stack 56 which has a duct or pipe 57 leading into top of kiln 24. Kiln 24 has duct 60 having gate 61 therein communicating with cooling duct 15, said duct 60 leading to the center of the floor for kiln 24. A duct 62 also communicates with the center of the floor portion of kiln 24 which communicates with draft duct 10 and has a gate 63 therein. Communicating with duct 62 is a duct 64 having a gate 65 therein, said duct 64 leading to vertically disposed stack 66 which has a pipe or duct 67 leading into the top of kiln 25.

Kiln 25 has duct 70 communicating with cooling duct 15 and has a gate 71 therein, said duct 70 leading to the center of the floor of kiln 25. A duct 72 leads from the center of the floor of kiln 25 and communicates with draft duct 10 and has a gate 73 therein. A duct 74 having a gate 75 therein communicates with duct 72 and also with the vertically disposed stack 76 which has a duct or pipe 77 communicating with the top of kiln 20.

Each of the kilns has a plurality of fire boxes 58 which is conventional and which receives the coal or other fuel for firing the kiln. The kilns are packed full of brick or other ceramic objects 78 in a loose manner so as to cause the heat and flame to pass thru all portions of the brick or other ceramic objects for drying and burning the same.

In the other form of my invention shown in Figure 3, cooling duct is indicated by reference character 100 having an exhaust fan 101 driven by a motor 102 and having an exhaust portion 103. A draft duct 104 is provided having an exhaust fan 105 driven by any suitable motor 106 and having an exhaust portion 107. A plurality of kilns 110, 111, 112, 113 and 114 are provided which are of the same structure shown in Figures 1 and 2. A duct 115 leads beneath kiln 110 and is connected to draft duct 104 and cooling duct 100 and has gates 116 and 117 therein and this duct communicates with the central floor portion of kiln 110 in the same manner as shown in Figure 2. A duct 118 is connected to duct 115 and has a gate 119 therein. Duct 118 communicates with lower portion of vertical stack 120 which stack has a pipe or other suitable duct 121 leading therefrom into top of kiln 111. Duct 122 leads beneath kiln

111 and is connected to ducts 100 and 104 and has gates 123 and 124 therein. Duct 122 communicates with the center floor portion portion of kiln 111.

Leading from duct 122 is a duct 126 having a gate 127 therein which duct 126 communicates with the lower end of vertical stack 128 which has a pipe or other suitable duct 129 leading into the top of kiln 112. Kiln 112 has passing therebeneath and communicating with the center floor portion thereof a duct 130 which communicates with ducts 100 and 104 and has gates 131 and 132 therein. Communicating with duct 130 is a duct 133 having gate 134 therein which duct 133 communicates with vertical stack 135 which has a pipe or other duct 136 leading to the top of kiln 113.

Kiln 113 has duct 140 leading therebeneath and communicating with the center of the floor portion thereof, and said duct 140 communicates with duct 100 and 104. Duct 140 has gates 141 and 142 therein. Communicating with duct 140 is a duct 143 having a gate 144 therein, said duct 143 communicating with the lower portion of stack 145 which has a pipe or other suitable duct 146 leading into the top of kiln 114. Kiln 114 has a suitable duct 150 leading therebeneath and communicating with the center of the floor portion thereof and this duct has the gates 151 and 152 therein.

The method of operation of the device shown in Figure 1 is such that it may be carried on continuously. Let us suppose that with gate 75 closed that kiln 20 is packed full of brick or other ceramic objects and gates 26 and 33 are closed and gate 29 is opened and fan 12 is started in operation and with the fire being in operation in all of the fire boxes in kiln 20 this fire will be continued approximately two days and ordinarily it takes about six days of firing with coal to produce the best grade of brick or other ceramic objects. After about two days of firing of kiln 20, gate 29 is closed and gate 33 is opened and, therefore, the draft which is necessary to be passed continuously thru kiln 20, instead of being drawn into draft duct 10 and the heat therefore wasted is led thru duct 30 and up thru stack 31 and thru duct 32 into the top of kiln 21 and with gate 34 closed and also gate 38 closed and gate 36 opened, the draft is pulled thru kiln 21 for approximately four days until kiln 20 is completed in burning. When kiln 20 is completely burned then the fire is drawn and at the same time gate 33 is closed and fire is started in kiln 21 and since kiln 21 has been pre-heated for several days to thoroughly dry the brick or other ceramic objects it takes approximately only one half time to complete the burning operation in kiln 21. With the fire going in kiln 21 and gate 33 being closed as well as gate 36 but with gate 38 opened, draft is drawn thru

duct 37 and stack 39 and duct 40 and thru kiln 22 and back thru duct 44 as gate 45 will be opened where gates 42 and 47 will be closed.

This operation will be continued around the entire apparatus, and while this is being continued, it is evident that with gates 75, 33 and 29 closed, gate 27 will be opened immediately after the firing operation has ceased in kiln 20 and fan 17 is placed in operation to draw the heat from kiln 20 so that the door which has been sealed up can be unsealed and the brick or other ceramic objects removed therefrom. This operation follows the burning operation around the complete circle so that by the time kiln 25 has been pre-heated and fire is ready to begin in kiln 25, kiln 20 will again be ready for operation as it will have been cleared and packed full of brick or other ceramic objects and the draft from kiln 25 instead of being pulled thru duct 72 into draft duct 10 by gate 75 being open, will be pulled thru duct 74, stack 76, duct 77 and thru kiln 20 and in this manner it is seen that a continuous operation can be carried on, thus saving a great amount of fuel in the burning operation.

The method of operation in the structure shown in Figure 3 is similar to that shown in Figure 1 except by the arrangement in Figure 3 the operation cannot be continuous because when kiln 114 has been in the process of burning the draft therefrom cannot be led thru another kiln but the firing operation will have to begin again with kiln 110.

In Figure 3 fire is started in kiln 110 with gate 117 open and fan 105 running. After approximately two days of burning in kiln 110, gate 117 is closed and gates 119 and 124 are opened and for the remainder of the burning of kiln 110 the draft is drawn from kiln 110 thru duct 115 and duct 118 and into the top of kiln 111 and thru duct 122 with gate 124 being opened. Of course, when kiln 110 has been completely burned and fire is started in kiln 111 then gate 119 will be closed and also gate 124 will be closed and gate 127 opened and the draft from the burning kiln 111 will be drawn thru kiln 112 with gate 132 opened.

This pre-heating of kiln 112 at any suitable time after the fire has been started in kiln 111, the draft being drawn thru kiln 112 a sufficient amount of times to thoroughly dry the brick therein so that the only fire needed is enough to glaze and finish the glazing and drying operation. The operation just described for kilns 110 and 111 and 112 is carried out on thru until kiln 114 has been completely burned and, of course, the operation can be completed by exhausting the burned kilns into cooling duct 100 by means of fan 101.

It is, of course, to be understood that while

a kiln is being pre-heated that its fire boxes will be sealed.

In the drawings and specification, there has been set forth a preferred embodiment of the invention and although specific terms are employed, they are used in a generic and descriptive sense only and not for purposes of limitation, the scope of the invention being set forth in the appended claims.

Claims:

1. Ceramic burning apparatus comprising a plurality of kilns arranged in a circle, a circular draft duct arranged on one side of the kilns, a circular cooling duct arranged on the other side of the kilns, means connecting the bottom of each of the kilns with both the draft duct and the cooling duct, gates in said connecting ducts located between the kiln and the respective ducts, a duct leading from the connecting duct of one kiln to the top of another kiln whereby the draft on a burning kiln can be conducted through the top of and downwardly thru another non-burning kiln to pre-heat the ceramic objects in the non-burning kiln.

2. Ceramic burning apparatus comprising a plurality of kilns a cooling duct and a draft duct, a duct connecting the bottom of said kilns to the cooling duct, a duct connecting the bottom of said kilns to the draft duct, a duct leading from the bottom of one kiln through the top of another kiln and means for opening and closing said ducts to draw the heat from the bottom of a burning kiln through the top of a non-burning kiln and out of the bottom of the non-burning kiln into the draft duct.

3. Means for creating a draft in a kiln for burning ceramic objects which comprises conducting means for the draft leading from the bottom of one kiln through the top of the next kiln and means for withdrawing the draft from the bottom of said next kiln.

4. Apparatus for burning clay products such as brick and the like which comprises a plurality of kilns having an inter-connecting duct between each kiln, each of said ducts leading from the bottom of one kiln and extending outwardly and upwardly and communicating with the top of the next adjacent kiln.

5. Apparatus for burning clay composition articles such as brick and the like comprising a plurality of spaced kilns, said kilns being connected in series by means of a duct leading from the bottom of one kiln into the top of another kiln and suction means for drawing heated air from the bottom of one kiln into the top of another kiln through said duct.

6. In apparatus for burning clay compositions comprising a plurality of kilns, a circulatory system for said kilns comprising a duct leading from the bottom of the first kiln into the top of the second kiln and from the bottom of the second kiln into the top of

the third kiln until all kilns are thus connected together and means for creating a partial vacuum in any selected duct to cause heat from one kiln to be passed into and through another kiln.

- 5 7. In an apparatus for burning clay compositions such as brick and the like comprising a plurality of spaced kilns, means for connecting the kilns together comprising a duct disposed between each kiln and having
- 10 one end thereof communicating with the bottom of one kiln and its other end connected directly to the topmost half of the next adjacent kiln and draft creating means for causing heated air to flow from the bottom of one kiln through said duct into the topmost half of the next adjacent kiln.
- 15 8. In an apparatus for burning clay compositions such as brick and the like, a plurality of kilns, a pair of spaced ducts, a transverse duct for each kiln disposed beneath each kiln and having its central portion communicating with the interior of the kiln and having its end portions communicating with said spaced ducts, a pair of gates in each transverse duct disposed on opposite sides of the kiln, an exhaust fan connected to one of the spaced ducts and an induction fan connected to the other spaced duct, a duct for each transverse duct connected at one end thereof with the transverse duct and at the other end thereof with the top interior portion of an adjacent kiln.

In testimony whereof I affix my signature.
NOAH B. KENDRICK.
